UNITED STATES PATENT OFFICE.

JOHN W. McCASLAND, OF CHICAGO, ILLINOIS.

DESIGN FOR AN AUTOMOBILE BUMPER.

Application filed January 15, 1927. Serial No. 20,403. Term of patent 3½ years.

To all whom it may concern:

Be it known that I, JOHN W. McCASLAND, a citizen of the United States, residing at Chicago, in the county of Cook and State of Illinois, have invented a new, ornamental, and original Design for an Automobile Bumper, of which the following is a specification, reference being made in the accompanying drawings, forming a part hereof.

In the drawings:—

I claim:

The ornamental design for an automobile bumper as shown.

Signed at Chicago, in the county of Cook and State of Illinois, this 20th day of December, 1926.

JOHN W. McCASLAND.
